UNITED STATES PATENT OFFICE.

THOMAS EDWARD KING, OF WESTFIELD, NEW JERSEY, ASSIGNOR TO HITCHINGS & CO., OF ELIZABETH, NEW JERSEY, A CORPORATION OF NEW JERSEY.

GREENHOUSE.

Application filed June 13, 1924. Serial No. 719,752.

This invention relates to improvements in greenhouses, and, more particularly, to sill-plates for topping the concrete side-walls of greenhouses. But while shown and described herein in connection with a greenhouse, my invention may also be used in connection with other classes of buildings.

In the construction of greenhouses, it is the practice to first construct a foundation, in which are set a number of supporting-posts to carry the superstructure consisting of standardized parts of iron or steel. The side walls, to a certain height, are usually constructed of concrete; and, according to the present practice, the construction of the side walls follows the erection of the superstructure.

Topping the concrete side-walls and rigidly united thereto are the sill-plates, abutting which are the glazed sashes, the sill-plates being firmly secured to the supporting-posts.

Heretofore, it has been the practice, when erecting the superstructure, to defer the placing of the sill-plates in permanent position until the mason was able to construct the side-walls. Then, in order to unite the sill-plate to the side-walls, the greenhouse contractor would return and place the sill-plates, bolting the same at suitable intervals to the supporting-posts. The sill-plates commonly used were flanged longitudinally, front and rear, so that one flange engaged the front face of the wall and one flange the rear face, thereby holding the side-wall firmly to the superstructure.

The object of my invention is to provide sill-plates of such construction that they may be placed in permanent position at the time the rest of the framework is erected; that is, before the erection of the side-wall, thereby obviating the necessity of the workmen making an extra trip to the greenhouse to set the sill-plates. Another object of my invention is to provide a sill-plate that will lend additional strength to the side-wall, and, in fact, to the whole structure.

My invention is illustrated in the drawings, forming a part of this application, wherein Fig. 1 is a view partly in elevation and partly in vertical section of a side-wall, sill-plate and supporting-post, and Fig. 2 is a section on the line 2-2 of Fig. 1.

Referring to the drawings in detail, A represents a concrete side-wall of a greenhouse, and B one of the supporting-posts suitably supported in a foundation of concrete, brick or other material (not shown). My improved sill-plate is indicated in whole at C, being formed, in cross-section, like a standard Z bar, and comprising an upper flange c and a lower flange c' and web c², the lower end of the lower flange c' being curved outwardly to turn water away from the side wall.

Necessarily, the sill-plate is transversely divided into a series of abutting sections, the number of these sections, depending, of course, on the length of the building. Preferably, each section is of sufficient length to reach from one supporting-post to another. The brackets D are arranged in pairs and hold the sections rigidly to the supporting-posts B, and, at the same time, keep the abutting sections in perfect alignment with each other and prevent tilting of the same. It is owing to the fact that the brackets D are shaped to suit the structural arrangement of the sill-plates that they are able to perform this requirement. Each bracket is substantially L-shaped, one leg D' being fixedly connected to the supporting-post B by screw-bolts D², while the other leg D³ is fixedly connected by screw-bolts D⁴ to the upstanding flange c of the sill-plate and has a bearing surface co-extensive with the width of said flange to prevent tilting of the sill-plate.

At suitable intervals along the under side of the sill-plate, are placed a number of tie-rods E, adapted to be imbedded in the concrete side-wall, and having arms or brackets e, turned inwardly, adapting them to be secured to the sill-plate, as with screw-bolts e'. These tie-rods assist to make a rigid connection between the sill-plate and side-wall, and their use is made possible by a construction of sill-plate that permits placing them in permanent position in advance of the building of the side-walls, and which enables the workmen to build the upper portion of the walls under a sill-plate which has one open side. A further advantage is that in the use of my sill-plate the side-walls may be built to make close contact with the under side of the same (thereby

lending additional strength to the structure) which is not possible with the sill plates now in use.

Having described my invention, what I claim is:

1. In a greenhouse construction, the combination with a foundation and supporting posts, of sill members positioned transversely of said posts and spaced an appreciable distance from the top of said foundation to permit the erection of a side wall thereafter, each of said sills embodying a web portion adapted to crown the top surface of said wall and having upwardly and downwardly directed flanges, the former flange being connected to said posts and the latter adapted to embrace a portion of the outer face of said wall.

2. In a greenhouse construction, the combination with a foundation and supporting posts, of sill members positioned transversely of said posts and spaced an appreciable distance from the top of said foundation to permit the subsequent erection of a side wall, each of said sills embodying a web portion adapted to crown the top surface of the wall and having upwardly and downwardly directed flanges, the former flange being connected to said posts and the latter adapted to embrace a portion of the outer face of said wall, the lower end of said flange being curved outwardly to shed water away from said wall.

3. In a greenhouse construction, the com-

bination with a foundation and supporting posts, of sill members positioned transversely of said posts and spaced an appreciable distance from the top of said foundation to permit the subsequent erection of a side wall, each of said sills embodying a web portion adapted to crown the top surface of the wall and having upwardly and downwardly directed flanges, the former flange being connected to said posts and the latter adapted to embrace a portion of the outer face of said wall, and a downwardly extending bracing member rigidly connected to the underside of said sill and adapted to be embedded in said wall during its erection.

4. In a greenhouse construction, the combination with a foundation and a supporting post, of a sill member permanently positioned transversely of said post and spaced above the foundation to permit the erection of a side wall thereunder, said sill member comprising a web portion adapted to crown the top of the side wall and having an upwardly and downwardly directed flange portion, the latter adapted to embrace a portion of the face of the side wall and a bracket having a leg secured to said upwardly extending flange of said sill member and the other leg being fixedly secured to said supporting post, and extending above the other leg to avoid interference with the subsequent erection of the side wall within the structure.

T. EDWARD KING.
